being preferably employed to avoid relative rotation as between the drive shaft and the drum hub. A plurality of interspaced reinforcing ribs 39 integrally merge with the underside of the reel hub or web 26, with lateral surfaces of the drum flange 8 and the drum hub 6.

At 27, an aperture of the reel seat 26 is disposed closely adjacent the web 19, near its junction with the winding drum flange 8, and at 15 another aperture is provided through the wall of the drum flange 8.

The storage reel is intended to store derrick cable whose length is in excess of that of the normal working cable required for a given relatively short length of boom. The storage reel 3 is designed to carry the excess length of cable, whenever the length of boom has been reduced through the removal of a section and less cable is therefore required to operate the boom.

When a boom length is to be changed, preferably the boom is generally placed in a horizontal position with the outer end resting on a support. Then if the boom is to be shortened, a section is removed and the remaining section assembled. To take care of the resulting excess of the cable the cable clamp 20, which is adjacent to the guide 16 is removed and the excess cable is drawn through the guide and the cable clamp reinstalled. Now, by revolving the drum so as to raise the boom, while manually holding the free end of the reserve cable taut, so as to permit it to be fed on the reel 3, the working cable is wound on the drum and the excess cable is also, during the same operation, wound on the cable reel. This averts the necessity for winding the excess cable on the reel manually, although, especially for relatively shorter lengths of excess cable, manual reeling may be resorted to.

Through the two apertures 15 and 27, the end of the complete continuous cable may be successively projected and the portion thereof intended to be employed as a reserve length of storage cable is looped over the arcuately formed channel guide 16, Figs. 2 and 5, and then wound around the storage reel 3, and when completely reeled upon said reel the extreme end of said reserve cable is anchored by clamp 23 to a laterally disposed portion of the surface 12 of the web 19, the clamp being secured to said web preferably by a U-bolt 51, Fig. 4, projected through any of the plurality of pairs of apertures 22 which are disposed at intervals through the web 19 near the juncture of said web and the brake drum flange 10.

During the operation of placing the end of the cable on the storage reel 3 when the full length of storage cable has been drawn through the apertures 15 and 27, Fig. 8, and after looping the cable portion 52 over the arcuate channel guide 16, a clamp 20 preferably similar to that shown at 23 is employed to tightly clamp the cable to the adjacent surface of the web 19.

The reserve or storage portion of the cable, after being wound upon the storage reel 3, thus has its free end 54 and also its other end disposed adjacent the guide 16 securely clamped to the web 19 so that rotation of the reel with the winding drum is entirely without effect upon the stored cable which is rigidly affixed to the web by both ends.

The cable guide 16 is rigidly secured preferably by welding or in any other suitable manner to the base of the web 19 adjacent to its juncture with the drum flange 8, being thus made integral with said web.

Figs. 2 and 3 best illustrate the manner of pro-

jection of the length of storage cable through the wall apertures 15 and 27, Fig. 8, better illustrating the nature of said apertures and the cable guide and the aforesaid cable clamps are best shown in Figs. 2 and 3.

The drawings show the derrick cable, whose free end, in the usual manner, is commonly directed over sheaves around a sheave at the end of the boom and thence returned to the crane cab or housing, where it is securely anchored on the frame of the machine, as preferably comprising in a single length the cable sections 53 and 54, whose intermediate portion 52 is hooked over the curved channel-shaped guide 16.

With the guide considered as the datum point, and the cable clamp 20 in place, each of the said cable sections are wound in the same winding direction, respectively on the drum 2 and reel 3. Thus the said intermediate portion 52 of the cable leading adjacent portions define what may be termed a hairpin loop, extending to the faces of the respective storage reel and work cable drum to take positions thereon as indicated on 54 and 53, Fig. 5, and in the view of Figs. 2, 3 and 4 with the free ends of the cable portions 53 and 54 disposed at opposite sides of the separating web or wall 19, rotation in the clockwise direction as viewed in Fig. 2 and in the counterclockwise direction as viewed in Fig. 3, of the entire unit comprising both the reel 3 and drum 2 of which the latter is of smallest diameter, both cable sections are wound on their respective reel and drum, during the same power effected rotation of the unit. During this same period of rotation of the unit drum reel and brake, the winding of the work cable 53 will exercise a pulling force on its free end to elevate the boom, which is the natural result of reeling in the derrick cable. At the same time the reserve cable is wound at a faster rate because of the greater diameter of the reel 3, and therefore at or before the time that the boom is fully elevated the length of reserve section of cable is completely wound upon said reel whereupon rotation of the unit comprising said reel and drum is discontinued and the brake is said to hold it stationary, whereby the end of the reserve cable is secured to the web 12 by operative placement of the clamps 23, Figs. 1, 2 and 3.

Figs. 10 and 11 illustrate cross sectional views 50 of the channel guide 16 affording a guide seat 17 for the portion of the cable, shown at 52 in Fig. 2, and in the form shown in Figs. 10 and 11 the channel guide is shown as having been formed integrally with the web 19 instead of welding a 55 separate channel shaped piece thereto as previously related.

As best illustrated in these figures, the cable wraparound ear 16 is provided with a relatively wider groove 17 in that end of ear disposed adjacent the opening 15 than at the end of said ear 16 disposed adjacent the storage drum bed, although in my preferred embodiment the depth of the groove remains the same.

The ear 16 is further curved inwardly and 65 downwardly, as best shown in Fig. 1, at its medial section to conform to the contour of associated portion 19' of the radial flange 19 wherefor the derrick cable is fed onto the grooved portion 17 of the cable wraparound guide 16 without an 70 abrupt change in its direction.

The lowermost portion of the rib 11 disposed nearest the holes 21-21 is curved as is the portion 19' to allow the cable fed thereover to the spool 3 to pass easily and without binding or 75 hindrance.

The perforation 15, as shown in Fig. 6, is preferably of shuttle shape, the small end of the opening being disposed adjacent the derricking drum bed 2 and the larger end thereof being disposed adjacent the opening 27 in the side wall portion of the disc.

I prefer further to so suitably dimension the cylindrical flange 8, as shown by the radials I to V, and more particularly in Fig. 9, that the taper of the flange decreases as that portion of the flange which is provided with the opening 15 is approached.

In order to strengthen the unitary winding drum, brake drum and storage reel structures in addition to the ribs 39, previously described, the radially extending flange or web 19 is also braced by the provision of radial ribs 11 dividing the web 19 into a plurality of radial portions 12, preferably five in number, and a radial portion 19, and in order to lighten the structure, these are provided with apertures such as those shown at 13 which may extend from the one to the other side of the web 19, said apertures being preferably interspersed between the ribs 11.

From the foregoing description it will be observed that the direction of winding considering both cable sections as a single length, proceeding from the outermost convolution of the one section to the outermost convolution of the other section, is reversed at the junction between the sections where the said intermediate portion of the cable length is wrapped around the arcuate channel-shaped flange element 16.

The reason for the reversal of winding direction is to accomplish the winding of excess cable on the reel by power while the boom is being raised as previously described. It is apparent that if the direction of winding were not reversed, the winding of rope on the reel would not occur when raising the boom.

The use of two cable clamps serves a very definite function, for the cable clamp adjacent to the guide passage through the flange serves to anchor the end of the working cable. The second clamp serves to anchor the end of the working cable after it has been wound on the storage reel.

Having thus described my invention in a particular embodiment thereof in a manner to clearly specify the construction which I prefer to those skilled in the art to which my invention appertains, I am aware that numerous and extensive departures may be made from the embodiments described herein without, however, departing from the spirit of my invention and the scope of the appended claims.

I claim:

1. An integral metallic cable winding unit for derricking cable comprising a pair of axially aligned, relatively contiguous, winding drums, each provided with a cylindrical hub and a pair of drum-end flanges, the hub of a first said drum being of substantially less diameter than, and supporting, that of the other drum, the axially inner flange of said first drum being apertured adjacent its outer hub surface and the other drum hub being apertured adjacent its axially inner flange to provide a cable passage between the drums, an arcuate transversely channel-shaped cable guiding channel element secured to the inner side of the axially inner flange of said other drum and said cable passage and the channel of said guide being so disposed that an intermediate portion of cable being hooked over said guide in

substantially hair-pin form whereby the cable, from one side portion of the guide, may, without being sharply bent, be directed by the guide and passage tangentially to said first drum hub surface, and the cable from the other side of the guide may be directed to tangentially engage the said other drum hub, whereby when said unit is rotated and the cable ends are held yieldingly taut, opposite portions of said cable, disposed toward its respective ends, may be concurrently wound, respectively, on the two drums.

5 2. The derricking cable unit substantially as set forth in claim 1, characterized by said axially inner drum-end flange of that drum whose hub is of greatest diameter, said flange having an unbroken periphery and being provided with an annular flange extending radially to an extent which is in excess of the width of the cable guiding element.

10 3. The derricking cable unit substantially as set forth in claim 1, characterized by the provision of a flange integrally secured to and affording a peripheral portion of the recited axially inner drum end flange of that drum whose hub is of greatest diameter, said flange having an unbroken periphery and being provided with an annular flange extending radially to an extent which is in excess of the width of the cable guiding element.

15 4. The derricking cable unit substantially as set forth in claim 1, characterized by the provision of a flange integrally secured to and affording a peripheral portion of the recited axially inner drum end flange of that drum whose hub is of greatest diameter, said flange having an unbroken periphery and being provided with an outermost brake surface adapted to be engaged by a non-rotatable braking element to retard the speed of rotation of the unit when the cable is being withdrawn from the first recited drum

20 which is of least hub-diameter.

25 5. The derricking cable unit substantially as set forth in claim 1, characterized by the provision of a flange integrally secured to and affording a peripheral portion of the recited axially inner drum end flange of that drum whose hub is of greatest diameter, having an outermost circumferentially continuous peripheral portion of substantially T-section in a transverse radial plane to afford a flange providing a peripheral outwardly facing brake drum surface and the recited cable guiding element being of less lateral extent than the relatively radially outwardly disposed portion of said brake drum flange.

30 6. The derricking cable unit substantially as set forth in claim 1, characterized by the provision of a flange integrally secured to and affording a peripheral portion of the recited axially inner drum end flange of that drum whose hub is of greatest diameter, having an outermost circumferentially continuous peripheral portion of substantially T-section in a transverse radial plane to afford a flange providing a peripheral outwardly facing brake drum surface and the recited cable guiding element being of less lateral extent than the relatively radially outwardly disposed portion of said brake drum flange.

35 7. The derricking cable unit substantially as set forth in claim 1, characterized by the provision of a flange integrally secured to and affording a peripheral portion of the recited axially inner drum end flange of that drum whose hub is of greatest diameter, having an outermost circumferentially continuous peripheral portion of substantially T-section in a transverse radial plane to afford a flange providing a peripheral outwardly facing brake drum surface and the recited cable guiding element being of less lateral extent than the relatively radially outwardly disposed portion of said brake drum flange.

40 8. The derricking cable unit substantially as set forth in claim 1, characterized by the provision of a flange integrally secured to and affording a peripheral portion of the recited axially inner drum end flange of that drum whose hub is of greatest diameter, having an outermost circumferentially continuous peripheral portion of substantially T-section in a transverse radial plane to afford a flange providing a peripheral outwardly facing brake drum surface and the recited cable guiding element being of less lateral extent than the relatively radially outwardly disposed portion of said brake drum flange.

45 9. The derricking cable unit substantially as set forth in claim 1, characterized by the provision of a flange integrally secured to and affording a peripheral portion of the recited axially inner drum end flange of that drum whose hub is of greatest diameter, having an outermost circumferentially continuous peripheral portion of substantially T-section in a transverse radial plane to afford a flange providing a peripheral outwardly facing brake drum surface and the recited cable guiding element being of less lateral extent than the relatively radially outwardly disposed portion of said brake drum flange.

50 10. The derricking cable unit substantially as set forth in claim 1, characterized by the provision of a flange integrally secured to and affording a peripheral portion of the recited axially inner drum end flange of that drum whose hub is of greatest diameter, having an outermost circumferentially continuous peripheral portion of substantially T-section in a transverse radial plane to afford a flange providing a peripheral outwardly facing brake drum surface and the recited cable guiding element being of less lateral extent than the relatively radially outwardly disposed portion of said brake drum flange.
